COMBINED CHAIR AND OTTOMAN

Gardner Leaver, East Hampton, N.Y., assignor to
Steelcase Inc., Grand Rapids, Mich.

Continuation-in-part of design application Ser. No.
24,841, Sept. 4, 1970. This application Jan. 27,
1972, Ser. No. 221,483

Term of patent 14 years

Int. Cl. D6—02

U.S. Cl. D6—37

FIG. 1

FIG. 2

FIG. 3

FIG. 4

FIG. 5

FIG. 6

FIG. 7

FIG. 8

FIG. 1 is a slightly elevated perspective view of a combined chair and ottoman embodying the design of my invention;

FIG. 2 is a front perspective view of the combined chair and ottoman;

FIG. 3 is a side perspective view of an alternative embodiment combined chair and ottoman embodying the design of my invention in which the headrest shown in FIGS. 1 and 2 has been removed;

FIG. 4 is a rear perspective view of the combined chair and ottoman of FIG. 1;

FIG. 5 is a plan perspective view of the combined chair and ottoman of FIG. 1;

FIG. 6 is a slightly elevated view of the ottoman alone, with the chair being broken away for convenience of illustration;

FIG. 7 is a perspective view of the combined chair and ottoman of FIG. 3;

FIG. 8 is a perspective view of the combined chair and ottoman of FIG. 1 with the ottoman shown rotated to the side.

This application is a continuation-in-part of my co-pending application Ser. No. 24,841, filed Sept. 4, 1970 and now Pat. No. D. 224,188 and entitled "Chair."

I claim:

The ornamental design for a combined chair and ottoman, substantially as shown and described.
